UNITED STATES PATENT OFFICE.

JOHN W. CALDER, OF PARNASSUS, PENNSYLVANIA.

RAILWAY-TIE.

No. 909,752.

Specification of Letters Patent.

Patented Jan. 12, 1909.

Application filed November 27, 1907. Serial No. 404,071.

To all whom it may concern:

Be it known that I, JOHN W. CALDER, a citizen of the United States, residing at Parnassus, in the county of Westmoreland and State of Pennsylvania, have invented or discovered new and useful Improvements in Railway-Ties, of which the following is a specification.

My invention relates to railway ties composed preferably of metallic structural shapes, such as Z-bars, and channels keyed together in pairs and preferably provided with rail fastenings of the type shown in Patent, No. 848,346, granted to me March 26, 1907.

Referring to the accompanying drawings, Figure 1 is a perspective of one of my improved ties, wherein I employ Z-bars; Fig. 2, a section of Fig. 1 on the line 2—2; Fig. 3, a cross-section of Fig. 2 on the line 3—3; Fig. 4, a perspective of the preferred form of a protector which may be used with my improved tie; Fig. 5, a perspective of a tie made of two channels with their flanges contiguous; Fig. 6, a perspective of a tie composed of a pair of channels placed back to back; Fig. 7, a cross-section of Fig. 5, the rail and fastening being shown; Fig. 8, a cross-section of Fig. 6, the rail and fastenings being shown; Fig. 9, a perspective of the preferred form of key for locking the sections of my ties together; Fig. 10, a perspective of one form of rail fastener; and Fig. 11, a perspective of a liner which I prefer to use to take up wear or looseness.

Referring to Figs. 1 to 4, 9, and 10, 1 represents a pair of Z-bars having their lower flanges 2 horizontal and extending away from each other and their upper flanges 3 horizontal and extending toward each other and preferably contiguous. The bars 1 are provided with L-shaped slots 4, arranged in pairs, one member of each pair being opposite the corresponding member in the respective bars. The L-shaped slots have a horizontal portion from which the vertical portion extends downwardly. I have shown the tie in Fig. 1 with two upper L-slots and three lower L-slots. The upper slots being preferably close to the flanges 3, and the lower slots are preferably close to the flanges 2, so as to brace and tie the bars 1 firmly together.

Keys 5 (Fig. 9) are inserted in the horizontal members of the pairs of L-slots 4 with the notches or slots 6 facing the vertical members of the slots 4. These slots 6, of

which there are two in each key, are spaced apart to correspond with the distance between the vertical members of the Z-bars 1 and the width of the slots 6 equals the thickness of the said Z-bars. It is clear, then, that, when the keys 5 have been inserted in the slots 4 as described with the slots 6 opposite the said vertical members of the bars 1 the keys may be slid toward the vertical members of the L-slots 4 and then rotated a quarter revolution, so that the reduced portions of the keys will stand in the vertical members of the slots 4 with the tops of the notches 6 resting on the lower ends of the slots 4. Thus placed, the keys cannot rotate back to a horizontal position and disconnect the bars 1 and they will prevent the said bars from independent lateral and longitudinal movements. The bars 1 may be readily taken apart by removing the keys 5 in an obvious manner.

The rails 7 are secured to the ties by means of the fasteners 8 which are similar to those shown in my said patent. The fasteners 80 have depending lugs 9 which extend through slots 10 in the top of the tie and at opposite sides of the rails. The part of the fasteners 8 above the ties is wider than the slots 10 and rests on the upper face of the flanges 3, as shown on Figs. 1 and 3. The fasteners have projecting fingers or lugs 11 which pass over the rail flanges and preferably touch the web of the rail, as shown on Fig. 2. The edges of the rail flanges rest preferably 85 against the shoulders 12 on the fasteners. The lugs 9 have the transverse slots 13, through which the keys or pins 14 pass, the ends of the keys or pins lying in the slots 15 in the bars 1, these slots being located with 90 their upper walls substantially in the plane of the lower faces of the flanges 3, so that the keys will have a long support against the said flanges and thereby prevent the bending or breaking of the keys. The keys 14 may 100 be held in place, as shown in my said patent, by the cotter pins 16.

Ballast is placed inside the ties, but preferably not in that portion provided with the fasteners 8. To keep the ballast out of this portion of the ties, I provide the protector shown on Fig. 4. This protector has the body 17 provided with the inturned flanges 18 spaced apart and proportioned to be slid over the flanges 2 of the ties. The central portion of the body 17 has at each end an upturned flange 19 and the lateral portions

of the said body have at each end the downwardly bent flanges 20. The body 17 is sufficiently long to have the flanges 19 include between them the lugs 9 of a pair of 5 fasteners 8. The flanges 19 keep the ballast away from the keys 14 and the fasteners and the flanges 20 aid in preventing endwise movement of the protector and the tie, the protector being secured to the tie by means 10 of the pins 21 in the holes 22 in the protector and the flanges 2.

In Figs. 5 and 7, the construction is the same as in Fig. 1, except that the flanges 2 of Fig. 1 extend into contact with each other, 15 the slots 10, being as shown in Fig. 1, cut half in each member of the tie.

In Figs. 6 and 8, the channels 23, instead of having their flanges facing each other as in Figs. 5 and 7, have their backs or vertical 20 members arranged opposite or facing each other. Their backs are spaced apart sufficiently to receive between them the lugs 9 of the fasteners. The keys 5 and 14 are applied the same as in the two preceding forms 25 of my invention. Slots 24 are cut in the upper angles of the channels to receive the upper portion of the fasteners, as shown in Fig. 8, so that the fasteners may be held by the 30 ends of the slots 24 from moving transversely of the rails.

In case there is any looseness in the fit of the fasteners 8 in the slots 10 or 24, the liners 25 (Fig. 11) may be placed in the outer ends of the slots, as shown in Fig. 2. These liners 35 are Z-shaped, the upper members resting on the tops of the ties, the middle or vertical members standing between the outer ends of the slot 10 or 24 and the outer ends of the fasteners 8, and the lower member lying 40 beneath the said fasteners. Thus, it will be seen that the liners will be firmly held in place as they cannot, owing to the said upper and lower members, fall or jump from their proper places. Liners of different thick- 45 nesses are provided so that the exact amount of looseness may be taken up by the use of liners of the required thickness.

I have extended the upper or wider portion of the fasteners well toward the outer 50 ends thereof so as to prevent any torsional strain on the keys 14 and to give the fasteners a larger and longer base. The slots 10 are preferably in the edges of both the flanges 3.

55 I do not restrict myself to the precise combinations and elements shown and described.

I claim—

1. In a metallic railway tie, the combination of a pair of metallic angle bars, having

therein opposite pairs of slots, keys extending through the pairs of slots and having therein notches to receive the walls of the said bars. 60

2. In a metallic railway tie, the combination of a pair of metallic angle bars, having 65 therein opposite pairs of L-shaped slots, keys extending through the pairs of slots and having therein notches to receive the walls of the said bars.

3. In a metallic railway tie, the combination of a pair of metallic angle bars having 70 therein opposite pairs of slots and shouldered keys seated in said pairs of slots to connect together said bars.

4. In a metallic railway tie, the combination of a pair of metallic Z-bars arranged with their upper flanges toward each other, means for securing the Z-bars together, rail fastening devices extending through slots in one of said flanges, and means for securing the said 80 devices in the said slots. 75

5. In a metallic railway tie, the combination of a hollow metal tie, rail fastening devices, means extending through the hollow in the tie for securing the fastening device to 85 the tie, and a protector for the securing means comprising a plate beneath the tie and an upturned and a downturned flange at each end thereof.

6. In a railway tie having basal flanges 90 and spaced side walls, a protector composed of a metal plate lying beneath the tie and having lateral flanges to receive the tie flanges, end flanges standing between the said side walls, and other flanges extending 95 downwardly into the ballast.

7. The combination of a metallic railway tie having slots at the sides of the rail flanges, rail fasteners in the slots, and removable liners between the outer ends of the slots and the outer ends of the fasteners, said liners consisting of flat material with the ends extending in opposite directions. 100

8. The combination of a metallic railway tie having slots at the sides of the rail flanges, liners seated in the outer ends of said slots and provided with means for supporting them and with extensions directed toward the rail, and rail fastenings insertible in said slots after the liners have been seated 110 and preventing the removal of the liners.

Signed at Pittsburg, Pa., this 20th day of November, 1907.

JOHN W. CALDER.
